(57) **CLAIM**

The ornamental design for an extendable comfort headrest, as shown and described.

DESCRIPTION

FIG. 1 is a front elevational view of an extendable comfort headrest in a first position;

FIG. 2 is a rear elevational view thereof in the first position; FIG. 3 is a right side elevational view thereof in the first position, the left side elevational view thereof in the first position being a mirror image of the right side elevational view in the first position;

FIG. 4 is a top plan view thereof in the first position;

FIG. 5 is a bottom plan view thereof in the first position;

FIG. 6 is a front perspective view thereof in the first position; FIG. 7 is a front elevational view thereof in a second position; and,

FIG. 8 is a top plan view thereof in the second position.

The broken lines in the drawings depict environmental subject matter only and form no part of the claimed design.
